UNITED STATES PATENT OFFICE

LAURENCE J. LESH, OF CHICAGO, ILLINOIS, ASSIGNEE, BY MESNE ASSIGNMENTS, TO
ASSOCIATED ELECTRIC LABORATORIES, INC., OF CHICAGO, ILLINOIS, A CORPORA-
TION OF DELAWARE

OSCILLATION DEVICE

Application filed May 11, 1928. Serial No. 276,970.

My invention relates to an improvement in "oscillation devices". The main object of my invention is the design of a device to produce oscillations of predetermined frequencies which can be readily controlled.

The device comprises a relay operating in conjunction with a three-element electron tube. The relay is of special design, which I have termed a tuned microphonic contact relay. This relay is provided with a magnet and a tuned reed armature upon which is mounted a microphone so positioned as not to interfere with the natural period of vibration of the reed but at the same time re-produce the vibrations set up by the reed.

The action of the microphone causes variations corresponding to the vibrations of the reed to occur in the grid or input circuit of the electron tube. Amplified circuits from the tube are transmitted from the plate or anode circuit to the winding of the magnet. This feed-back arrangement from the output circuit of the tube to the winding of the magnet causes oscillations to be set up in the circuits which correspond to the frequencies to which the reed is tuned or adjusted.

As the reed itself is the controlling factor as to the frequency of the oscillations, it is only necessary to provide a reed which will vibrate to the frequency desired in order to produce oscillations corresponding to that frequency.

The microphone may be of any well-known type such as illustrated and described in Patent No. 1,324,357, granted to H. A. Laree, December 9, 1919. The cup containing the granular carbon, as disclosed in the patent, is of the type which is mounted upon the reed armature.

My invention is illustrated in the accompanying drawing, wherein Fig. 1 shows a plan view of the tuned microphonic contact relay with circuit co-operating with an electron tube.

Fig. 2 is a side view of the relay.

Referring to the figures, it will be noted that the relay comprises two magnet windings 8 and 9 mounted upon a metal base 1. This base is provided with a lug or extension 2 through which pass two adjusting nuts

3 and 5 and the screws 4 and 6 for holding or positioning the magnets 8 and 9. The base 1 is also provided with the extension or lug 11 upon which is mounted a tuned reed 10, by means of the three screws 29. This reed extends across the pole pieces of the magnets 8 and 9, as shown in Fig. 1.

Mounted upon the reed is the microphone or cup 21 containing granular carbon or other suitable material. This cup is mounted upon the reed by means of the screw portion 22 threaded therein and positioned or locked by means of the nuts 23 and 24. The lug or extension 13 forming a part of the base 1 supports a contact spring 15 mounted thereon and insulated therefrom by the insulating washers 16. A screw 14 passes through the washers and the lug 13 and is held in place by the lock nut 18. The contact spring 15 extends to the cup 21 and is attached thereto by means of the nut 20 upon the threaded projection 19 which passes through an opening in the spring 15.

A set of terminals 26, 27, and 28 are mounted upon the base 1 by means of the screw 25 and insulated from one another by means of the insulating washers 40, as shown in Fig. 2. The terminal 28 is, however, in contact with base 1.

The electron tube 40 comprises the cathode 41, grid 42, and anode 43.

The winding of the magnets 8 and 9 are in series and are connected to the terminals 26 and 27. These terminals are connected to the anode 43 and the battery 46 in series with winding 49 of transformer R, forming the output circuit of the tube 40. The terminals of the microphone 21 are connected respectively to terminals 17 and 28. These terminals in turn are connected to battery 47 and the winding 44 of transformer T, and to the grid 42 through winding 45 of T. The filament or cathode 41 is supplied by a source of battery 48 in the usual manner.

From the foregoing, it will be noted that the microphone 21 is included in the grid circuit of the tube 40, transformer T and the windings of the magnets 8 and 9 are included in the anode or output circuit of the tube 40 in series with winding 49 of the transformer R.

As the output circuit is fed back into the windings of magnets 8 and 9 and these magnets control the operation of the microphone 21 by means of the tuned reed 10, oscillations will be set up in the circuit corresponding to the frequency of the vibrations set up in the reed 10.

10 The anode circuit includes the winding 49 of the transformer R, and consequently the current is induced in the winding 50 of the transformer which is connected to the output circuit leads 51 and 52.

15 These leads may extend to devices which are tuned to respond to the transmitted oscillations.

15 What is claimed is:

20 1. In an oscillating device, the combination of an electron tube having a cathode, grid, and anode, an electro-magnet provided with a tuned magnetic reed having a microphone mounted thereon, an input transformer and an output transformer, an electrical circuit including the anode, winding of said magnet and the primary winding of said output transformer, an electrical circuit including the microphone, a source of current and the primary winding of said input transformer, and an electrical circuit including the secondary winding of said input transformer and the 25 grid of said tube.

25 2. In an oscillating device, the combination of a base plate having a magnet and a tuned reed mounted thereon, a two element microphone having one element supported by 30 said reed, a spring mounted on said base plate and supporting the other element of said microphone, a circuit including a source of current, said tuned reed, said microphone, and said supporting spring, and an amplifier 40 having an input circuit coupled to said first circuit and an output circuit including said magnet.

3. In combination, a magnet having a tuned 45 reed armature, a two element microphone having one element anchored to said armature, a spring supporting the other element of said microphone, a circuit including a source of current, said armature, microphone and spring, and the primary winding of a transformer, and an amplifier having a grid circuit 50 including the secondary winding of said transformer and a plate circuit including said magnet.

55 In witness whereof, I hereunto subscribe my name this 8th day of May, A. D. 1928.
LAURENCE J. LESH.
